RETORT FURNACE

Application filed March 6, 1928. Serial No. 259,406.

This invention relates to metallurgical reduction furnaces.

One object of the invention is to provide a furnace of the character described which includes an improved retort for the continuous treatment of the mineral.

Another object of the invention is to provide a retort, the gases wherein may be exhausted at any desired pressure.

10 Another object of the invention is the provision of a furnace of the nature set forth comprising improved means for externally firing the retort.

15 A further object of the invention is to produce a furnace of the type specified wherein the setting of the retort co-operates therewith to furnish a substantially gas tight compartment about the retort at the openings of the latter for obviating leakage of air 20 thereinto.

Still another object of the invention is the production of a furnace of the nature referred to in which an improved seal is provided at the opening of the retort.

25 A still further object of the invention is to create a furnace of the type mentioned in which a uniform temperature gradient may be maintained along the retort.

Further objects will be seen to reside in the 30 provision of a furnace having an externally fired retort in which the retort and furnace lining are made of suitable refractory material to withstand the temperature generated, and the furnace lining to sustain the 35 pressure of the combustion gases; in which the retort is of a rotary type and includes means to scrape the interior wall of the retort and to aid in the mixing of the mineral therein; and in which the fuel is consumed ac- 40 cording to the principle of surface combustion in improved blocks of refractory material; the feeding of the fuel being prefera- 45 bly taken care of by automatic temperature control; and in which an improved system 50 for the circulation of the combustion gases about the retort is provided; and in which the volatile gases generated in the retort are withdrawn at the low temperature end there- 55 of.

In order to indicate the practical coaction

and the functional relationship of the parts of the apparatus, and also by way of general description, reference may advantageously be had to the method of use and the results obtained by the invention. The same is particularly adapted for the reduction of ores by coal or other carbonaceous materials out of contact with air and without the deleterious influence of the presence of combustion gases. Therefore a retort is provided 55 which is heated without combustion therein, and preferably externally. The gases generated by the reduction are rapidly 60 continuously withdrawn as fast as generated by means of pumps or the like, and causing a 65 decreased ambient pressure in the retort. Hence the latter must be sealed tight, and as the charge is continuously fed into and out of the retort simultaneously with the forcible 70 exhaustion of the gases, the retort has means 75 to permit such movement of the charge without entrance of air. As the charge is in finely divided form, and constant agitation thereof is necessary, the retort is preferably rotatable 80 and may be inclined at an angle to the horizontal so that the charge is simultaneously 85 uniformly agitated and fed through the retort. The exhaustion of the gases from the retort is preferably spaced from and independent of the movement of the finely divided charge for assuring uniformity in operation and reliability in control. The retort rotation requires a relatively light retort, although the apparatus is intended for large 90 scale industrial application; therefore the retort includes a metal component or may be wholly made of metal for combined strength 95 and lightness. Moreover, the transmission of heat into the retort, as from external heating means is thereby increased. For maximum efficiency of heat transfer, a highly radiant or incandescent heating means, operating as by surface combustion may be employed outside of the retort, and which may thus consume the gases generated in the retort itself. To prevent burning the retort, the heating means is spaced along the retort wall to maintain temperatures therein insufficient to melt the metal or gangue. Uniform 100 peripheral heating may be obtained by

the provision of circular heating means, which may, moreover, be arranged to prevent flame contact with the retort. An automatic temperature control may be utilized co-ordinated with the charge feeding and the exhausting means whereby the exhaustion of gases from the retort is regulated in proportion to the generation of gases, and to maintain a predetermined general pressure-temperature relationship in the retort. By arranging the heating means to afford a temperature gradient, the reduction of the ore gradually increases to a point of substantial completeness, and the gases generated may, in course of exhaustion serve to impart heat to the incoming charge. Thus a solid carbon reduction of an ore may be quickly and completely attained under a reduced pressure ambient with constant removal of all gases as fast formed and under low temperatures insufficient to melt the metal or gangue produced. Other features and functions of the apparatus are more particularly described hereinafter.

25 Other objects will in part be evident and in part pointed out hereinafter.

With the aforesaid objects in view, the invention consists in the novel combinations and arrangement of parts hereinafter described in their preferred embodiments, pointed out in the subjoined claims, and illustrated in the annexed drawings, wherein like parts are designated by the same reference characters throughout the several views,

35 and in which—

Figure 1 is a sectional elevation of a furnace embodying the invention.

Fig. 2 is an enlarged fragmentary section showing details of the retort seal.

40 Fig. 3 is a similar view showing the firing means.

Fig. 4 is a similar view showing the low temperature end of the furnace.

Fig. 5 is a similar view of the intake end 45 of the furnace.

Fig. 6 is a front elevation of the furnace.

Figs. 7 to 10 are enlarged sectional views taken on corresponding lines of Fig. 1.

50 Fig. 11 is an enlarged vertical sectional view taken on line 11—11 of Fig. 1 and showing a drive for the retort.

Fig. 12 is a vertical sectional view taken on line 12—12 of Fig. 3.

55 Fig. 13 is an enlarged fragmentary sectional view of a portion of the apparatus shown in Fig. 1.

The advantages of the invention as here outlined are best realized when all of its features and instrumentalities are combined in one and the same structure, but useful devices may be produced embodying less than the whole.

It will be obvious to those skilled in the art to which the invention appertains, that the same may be incorporated in several different

constructions. The accompanying drawings, therefore, is submitted merely as showing the preferred exemplification of the invention.

70 The herein described furnace is particularly adapted for use in the invention on a process of mineral reduction and metal extraction as described in my co-pending application for patent, Serial No. 208,103, filed July 25th, 1927.

75 The process mentioned may be defined for example, as consisting in heating an iron bearing mineral and coal in a heating chamber in finely divided intermixed condition, 80 reducing the mineral by the use of the fixed carbon in the coal out of contact with air at a temperature approximately between 700° C. as a minimum for coking coals and 950° C. as a maximum for non-coking coals, and rapidly removing from said chamber the gaseous products of the reduction and the volatile substances liberated.

85 Referring in detail to the drawings, 15 denotes a furnace embodying the invention. The same includes the walls and roof 16 of the furnace made of a high temperature material, as for example, silica, and resting upon a concrete floor 17. Within the furnace is mounted a cylindrical retort 18, at one end of which is a hopper 19, and at its other end a discharge device 20. The said hopper may receive the pulverized mineral and coal according to the process hereinbefore mentioned.

90 The retort or heating chamber 18 is coaxial with the furnace chamber 21 and is of smaller diameter than the same to provide an annular firing space. The said retort may be made of any suitable material, as, for example, mild steel which has been chromo-plated, or also of a chrome alloy steel. The 95 said retort is rotatable and is likewise downwardly inclined toward its discharge end in order to constantly feed forward the material therein. Though the retort is shown as being cylindrical it may also be conical, and, in cross section, may be polygonal, within the scope of the invention.

100 To afford connection between the retort and the hopper, the latter is provided with a neck 22 aligned with the retort. Said neck extends into the retort, and circular flanges are provided that constitute a slip connection 105 23 affording substantially gas tight communication between the retort and the hopper. In the bottom of the hopper is a feed screw 24 mounted on a hollow shaft 25. The said hollow shaft 25 is secured to the retort by an internal bracket 26 so that the screw 24 rotates in unison with the retort. At its other end this shaft is journaled in the bearing 27 of the hopper. An exhaust pipe 28 for 110 gases generated in the retort may extend through the said hollow shaft, whereby the gases in the retort may be rapidly withdrawn 115

120

125

130

therefrom, and any desired pressure maintained by any suitable means, such as any pump *P*, operating preferably through a conventional tar or dust trap *T*.

5 The discharge device 20 is mounted adjacent to an end plate 29 that is strongly secured to the furnace wall to close this end of the firing chamber. The said plate is formed with an annular groove 30 to receive the edge 10 of the enlarged cylindrical end extension 31 of the retort. The said extension 31 constitutes a positive-acting rotary conveyor, being provided with spaced plates 32 that form a series of pockets 33 disposed about the axis 15 of the rotor. A plurality of circular wall members 34 are rigidly secured to the plate 29 and form closures for the pockets 33. The said members 34 are connected together by a cover plate 35 for the retort, which plate is 20 in spaced substantially parallel relation to the end plate 29. The plate 35 is formed with a bottom opening 36 that gages and regulates the flow of mineral from the retort into the pockets 33. For adjustment of the material 25 from the retort, the gage plate 35 is vertically movable, or may be replaced by another similar plate having an opening 36 of a different area. It will be seen from Fig. 9 that the conveyor plates 32 form a closure with the 30 circular plates 34 that substantially prevents air from flowing into the retort through the discharge device. The pockets 33 raise the material therein to the top of the device 20, after which this material is dumped into 35 the spout 37 through which it is discharged.

The device 20 can be modified in many ways, and still provide broadly, a combined closure for the retort, and a positive conveyor, having simplified and improved coaction with the heating chamber.

40 It will be understood that the device 20 can be used also at the intake end of the retort to discharge material from the hopper into the retort, the screw 24 being eliminated, and the exhaust pipe 28 being extended through the plate 35. The screw and the device 20 may both be regarded as representing positive conveyors that rotate with the retort.

50 To scrape from the wall of the retort any material that may adhere thereto, a stationary shaft 38 is extended centrally through the retort and is journaled on brackets 39 secured thereto. The said shaft projects 55 through the plate 35 and is secured at one of its ends in the end plate bearing 40. Where the shaft passes through plate 35, a slot may be provided if vertical adjustment of the said plate is desired as aforesaid.

60 Extending downward from the shaft 38 at an angle with the vertical are a series of arms 41 spaced along the shaft. To the lower end of said arms is attached a mixing and scraping device which may take the form 65 of a continuous chain or flexible mat 42 that

rests on the bottom of the retort. With the latter rotating in the direction of arrow *a*, the said mat partly depends from the arms 41 toward the vertical central plane of the retort. Thus the mat effectively scrapes loose 70 from the retort wall any adhering material, and at the same time aids in the mixing of the heaped material *M* in the retort.

The furnace is fired by surface combustion. For this purpose masses of porous refractory material are disposed circumferentially about the retort to impart heat thereto from all sides with substantial uniformity. The combustion gases on leaving the masses of refractory material are caused to circulate 75 about the retort to further impart heat thereto. Spaced burner nozzles are arranged in any desired number to discharge gas and air under pressure into the masses of refractory, and with the object of obtaining a substantially even radiation of heat therefrom, on the retort. Further, the combustion means is so constructed, that the burning gases substantially permeate all parts of the refractory. On leaving the refractory masses, the gases are caused to travel therefrom along the retort for uniformly heating the same in conjunction with the action of the refractory masses on the retort.

80 The refractory masses 43 are made of any suitable porous material and may be of ring form, coaxial with the furnace and seating against the inner wall of the chamber 21. The said masses 43 are in spaced relation 85 at their inner peripheries with the wall of the retort to avoid corrosive action on the latter.

The material of which the said refractory consists may be graphite mixed with tar and calcined to drive off the volatile constituents 90 of the tar, thus leaving a porous block. Then again, carborundum or alundum refractory may be formed into a ring.

95 Each of the rings 43 forms a high temperature combustion chamber being inclosed 100 on all sides except at one portion which forms an outlet 44 for the gases. Preferably the inclosure aforementioned is formed by glazing the said ring.

105 Although the heating rings exemplify the preferred embodiment of the invention, it will be appreciated that surface combustion can also be practised in other ways well known in the art, and the retort heated in a compact furnace out of contact with the flame, by direct or semi-direct radiation, with or without contact with the products of combustion. The primary object is to obtain uniform heating peripherally and longitudinally of the retort.

110 The porosity of the ring and the voids therein are predetermined to permit a desired quantity of fuel to be consumed therein and to pass therethrough at a given pressure. Since the gas is burned with but 1% 115

of excess oxygen, combustion proceeds with explosive velocity, and the flame will be slightly reducing to obviate oxidation of the retort.

- 5 Communicating with each ring 43 is a burner 45 having a plurality of nozzles 46 branching therefrom in opposite directions to inject the gas and air into the ring. The combustion thus takes place in two streams of 10 flame moving upward toward the outlet 44. The mixture of gas and air is discharged from the burner nozzle at a pressure of approximately fifteen pounds per square inch, and the burner is carefully packed with fire 15 clay 47 and the like, or other insulating material. In this way concentration of heat at the burner is avoided.

In the furnace chamber 21 the pressure of flue gas is considerable and may be as high 20 as several pounds per square inch. To take care of this pressure, the inner wall of the said chamber is glazed, rendering the furnace wall substantially impervious to the flue gas.

- 25 Gas and air are fed through separate pipes 48 and 49 respectively into a central mixing chamber 50, from which they pass through a butterfly mixer 51 into a burner 45. The said butterfly mixer may be of any suitable 30 type but preferably includes a fan (not shown) which is rotated by the thereon impinging air and gas and serves to thoroughly intermix them.

An automatic temperature control 52 may 35 be provided operating with the usual thermocouple 53 to control the supply of mixture fed to the burner by means of a valve 54.

Any other suitable type of burner and control therefor can be used depending, in part, 40 upon the method of firing the furnace.

By means of the said temperature control and the spacing of the combustion blocks as shown, a desired temperature gradient can be easily maintained in the furnace, this 45 ranging from 950° C. as a maximum to approximately 28° C. at the retort inlet. Also economy in operation of the furnace is obtained, this result being aided by the fact that the gases generated in the retort are 50 exhausted at the rear end thereof through the aforesaid suction pipe 28.

The gases leaving the refractory blocks 55 through the outlets 44 therein are caused to circulate about the retort by means of baffles 55. These are made of any suitable heat 55 resisting material and project from the furnace wall into proximity to the retort. Co-acting with these baffles is a flue by-pass 56 in the roof of the furnace whereby, after circu- 60 lation of the gases has occurred, the same are rapidly transferred to circulate about the material receiving end of the retort so that the available heat of the fuel is rendered as high as possible.

65 Secured about the said retort are a plu-

rality of flanged members 57 that have sliding sealing contact with the baffles 55.

Between the first two combustion blocks 43a and 43b at the high temperature end of the furnace is an annular passageway 58 into which a single baffle plate 55 extends centrally between the adjacent blocks and somewhat more than half way down the sides of the retort. Accordingly gas leaving block 43a is caused to flow downward around the retort and then upward on the other side of the baffle and into the by pass 56, as shown by the arrows.

70 Between the blocks 43b and 43c, a pair of spaced downward extending baffles 55 are 75 provided forming therebetween a passage 59 communicating with the by pass 56. Coacting with one of these baffles is another upward extending baffle 55a, so that an annular portion 60 of the furnace is shut off from the combustion gases. The arrows clearly indicate the circulation of the flue gas.

80 Between the combustion blocks 43c and 43d, a plurality of downward extending baffles 55 are provided. A passage 61 connecting with the by pass 56 is formed between the block 43d and the adjacent baffle. Coacting with the last mentioned baffle, is an upward extending baffle 55a, so that the flue 85 gas from block 43c is caused to circulate 90 twice down and up before entering the by pass 56.

Beyond the combustion block 43d, but in 95 proximity thereto are a plurality of spaced 100 downward extending baffles 55 with one of which coacts an upward extending baffle 55a. Between the said baffles 55 there communicates a passage 62 through which flue gas from block 43d passes into the flue by-pass 56. An annular passageway 63 is formed between 105 the said coacting baffles on one side and engaging baffles 64, 65 on the other side. The function of this passageway 63 will be hereinafter described. Beyond this passageway 63, the flue by-pass 56 discharges through an opening 66 into the low temperature end of 110 the furnace chamber.

The said low temperature end of the furnace chamber is broken by a series of uniformly spaced downward extending baffles 67 and a similar series of upward extending baffles 68. The baffles 67 and 68 are staggered 115 with respect to each other so that a uniform and continuous circulation of flue gas about the retort is insured. The flue gas is finally 120 discharged through a flue 69.

125 It will be understood that while reference has been made herein to a specific baffle construction and arrangement, the same is capable of a high degree of variation as is well known in the art, within the scope of the invention.

130 It is seen that this furnace is through the circulation of gases hereinbefore described, particularly adapted for producing a uni-

form temperature gradient in the retort, and that a proper balance can be obtained as between heat obtained from the combustion blocks and that obtained directly from the combustion gases by proper proportioning of parts, with the object of obtaining uniform heating. It is noted that heat is furnished to the material in the retort by conduction at the bottom of the retort, and by radiation from the top and sides of the retort. Uniform heating of the material is accordingly provided.

To afford support to the retort intermediate of its end bearings the retort is surrounded with rings 70 of metal, or the like, which seat on spaced rollers 71. This supporting construction is housed in the annular passages 60 and 63. Plugs 72 of fire clay or similar material are removable for inspection or repair of the rollers.

To rotate the retort, any suitable drive may be provided, as shown in Fig. 11. A motor 73 by means of reduction gearing 74 turns a main gear 75 that extends around the retort in proximity to the hopper.

The invention thus produces an improved heating chamber or retort, from which the gases may be withdrawn rapidly and exhausted at any desired pressure, to aid the reaction and the obtaining of a comparatively pure product, and in which the operation is continuous and uniform both from a mechanical and chemical viewpoint, the heating being uniform and even, and the temperature gradient accurate, the invention being adapted for long use with a minimum of inspection, repair, or cleaning.

Various changes and modifications can be made in the invention, the construction shown being intended in an illustrative not in a limiting sense, and it will be appreciated that within certain principles of the invention, various objects may be substituted for the retort, and the claims are to be construed according to the spirit of the invention, the terminology being relied on to clearly define the invention.

I claim:

1. A device of the character described, including a furnace, a retort therein having a receiving end and a discharge end, refractory material in the furnace, and spaced means to raise the refractory to incandescence to form a series of zones radiating heat on the retort at the portion thereof toward the discharge end, and baffles between the retort and the furnace wall and intermediate of said zones, there being a by pass in the furnace to cause the baffled combustion gases to flow to the other portion of the retort.

2. A device of the character described, including a retort, a positive conveyor within the retort coaxial therewith to move a charge longitudinally of the retort, unitary means to rotate the retort and the conveyor, said conveyor

including a plurality of pockets, and a relatively stationary closure means for the pockets, said means being constructed to permit materials in the retort to enter a lower pocket and to discharge the materials from an upper pocket.

3. A device of the character described, including a retort, a positive conveyor substantially concentric with the retort to move a charge longitudinally with respect to the retort, and to rotate the conveyor and the retort at the same speed, and other means to close the pockets at a predetermined portion of the path of travel.

4. A device of the character described, including a rotary retort, a relatively stationary transverse means including a drum therefor, and rotary means along the edge of the drum forming therewith a closure for the retort, said rotary means having a plurality of recesses angularly spaced around said drum and closed thereby, each of said recesses coacting with the drum to receive a charge from the retort at one side of the said drum, and discharging the said charge in its high position on the other side of said drum.

5. A device of the character described, including a furnace, a rotary retort therein, the furnace having a mass of porous refractory in proximity to the retort and extending therearound, but having a clearance space with the retort, and means to internally fire the said mass.

6. A device of the character described, including an elongated retort, a furnace enclosing the same, internally fired elements spaced along the retort on the outside thereof, at one end portion of the retort, and means to receive the products of combustion at a plurality of points in proximity to said elements and discharge the same for circulation about the other end portion of the retort.

7. A device of the character described, including an elongated retort, a furnace enclosing the same, internally fired elements spaced along the retort on the outside thereof, at one end portion of the retort, baffles for the products of combustion intermediate of said elements, and means to receive the products of combustion at a plurality of points in proximity to said elements and discharge the same for circulation about the other end portion of the retort.

8. A device of the character described, including a retort, means to externally heat the same, means to feed a charge into the retort at one end of the same, means to discharge the charge at the other end of the retort, and means at the intake end of the retort to withdraw gases from the retort, the means for heating the retort including firing means at the discharge end thereof, and means to circulate the products of combustion of the firing means about the inlet end of the retort.

9. A device of the character described, in-

cluding a furnace chamber, an elongated retort therein, means to feed a charge into the retort at one end thereof and to withdraw the charge from the retort at the other end thereof, of, combustion means in the furnace chamber at the discharge end portion of the retort at points spaced lengthwise of said portion to heat the same, the products of combustion flowing to the inlet end portion of the retort, and a plurality of spaced baffles at said inlet end portion to cause the products of combustion to circulate around the retort.

10. A device of the character described, including a furnace, an elongated retort therein, the retort having a comparatively low temperature end and a relatively high temperature end, and combustion means at the high temperature end, the furnace having a by pass in the wall thereof to cause the products of combustion to flow to the low temperature end of the retort.

11. A device of the character described, including a furnace, an elongated retort therein, the retort having its ends at different temperatures, combustion means at the high temperature end of the retort, and channels for the products of combustion between the retort and the wall of the furnace, the furnace having a by pass communicating with the channels to receive the products of combustion therefrom and cause the same to flow to the low temperature end of the retort.

12. A device of the character described, including a furnace, a retort therein, refractory tubes in the furnace extending inward of the furnace wall, and combustion means to internally fire the tubes, said tubes being spaced to provide radiation on the retort from the walls of the tubes facing the retort as well as from the side walls of said tubes, said tubes being filled with porous refractory material.

13. A furnace for reducing iron ores mixed with carbonaceous fuels in a substantially air tight retort, at temperatures which will not cause combustion in the retort or melt the iron, including means for feeding the materials to the retort and discharging same, means for keeping the materials mixed, heating means for said retort of refractory materials to be heated to incandescence, means to regulate the flow of materials into and out of the retort, means to continuously exhaust the gases developed in the retort from the materials being treated therein, and means to regulate the flow of heat producing elements to the refractory heating means, coordinated with the heating means to produce and maintain predetermined temperature limits in the retort.

14. A furnace for reducing iron ores in a substantially air tight rotary retort, external heating means of incandescent refractory materials, means to control the combustion of combustibles and air therein, with means to

continuously exhaust the gases developed in the retort from materials therein, means for feeding the materials into and out of the retort, means to apply the heat to the retort in a rising temperature gradient from the inlet end of the retort to the outlet end, the refractory heating means being spaced away from and along the retort walls.

15. A furnace for reducing metal bearing ores, consisting of a substantially air tight retort, enclosed therein, heating means being provided of refractory materials in which combustion takes place under surface combustion temperatures, means to pass the hot exhaust gases around the retort after passing through the refractory heating means, means to control the flow of combustibles and air to produce and maintain the predetermined temperature limits, means to control, agitate, and feed the materials into, through and out of the retort, means to continuously exhaust the gases developed in the retort from the materials being treated therein as fast as developed.

16. A substantially air tight retort and enclosed elongated tubular combustion heating means for heating the retort by radiation, the retort being out of contact with the burning gases in the heating means producing the heat, and with the means in which the combustion is taking place, said heating means being spaced away from and along the retort walls to produce and maintain uniform heating conditions, the heat transfer being by conduction and radiation to the retort and the materials therein under treatment, and means to control flow of air and fuel gas to produce and maintain a temperature gradient in the retort and materials being treated.

17. A substantially air tight retort and enclosed combustion heating means therefor of sufficient length to afford a substantial travel for the fuel consumed therein, the materials being heated in the retort, and the retort being out of contact with the burning gases in the heating means producing the heat, and with the means in which the combustion is taking place, said heating means being spaced away from and along the retort walls to produce and maintain uniform heating conditions, the heat transfer being by conduction and radiation to the retort and the materials therein under treatment, and associated means for continuously charging and discharging the materials being treated, and means to continuously exhaust the gases developed in the retort from materials being heated.

18. A furnace for reduction of metal bearing ores having an externally heated retort, in which the retort is made of materials capable of withstanding high temperatures, from heat developed in refractory materials surrounding the retort, enclosing walls for

- the refractory materials sustaining the pressure of the combustion gases burning in the refractory with surface combustion, and the temperatures causing incandescence in the 5 refractory material surrounding the retort, the refractory heating materials and enclosing walls being spaced away from and along the walls of the retort in which the materials to be reduced are being treated.
- 10 19. A furnace for reducing metal bearing ores including a retort externally heated, by means of refractory materials spaced away from and along the walls of the retort, the combustion of fuels and air being in the refractory materials, the heat transfer to the materials being treated in the retort being by conduction and radiation, means to feed materials into the retort at one end, and means to discharge the material at the other 20 end, means to withdraw the gases continuously from the retort developed from the materials being treated, means to cause the combustion gases in the refractory materials surrounding the retort and the exhaust gases 25 therefrom to flow towards the intake end portion of the retort on the outside of the walls of the retort shell.
20. An apparatus for the low temperature reduction of iron ores with solid carbonaceous fuels intimately mixed therewith, including a rotary retort, automatic means for rotating the same, the retort having means associated therewith for moving the charge into and out of the retort, said means being 30 co-ordinated with the retort to operate according to the speed of rotation of the latter, means extending in a curved line around the outside of the retort for externally heating the retort, means for automatically controlling the heating means, closure means for the ends of the retort through which the materials enter and discharge from the retort, and means for exhausting the gases from the retort through said closure means.
- 45 21. An apparatus for the heat treatment without agglomeration of a pulverized charge of iron ore and coal, including a rotary metallic inclined retort of cylindrical form, a furnace enclosing said retort, stationary radiant firing means in the furnace for uniformly peripherally heating the retort from the outside thereof, burner means so co-ordinated with the radiant firing means and the retort as to impart a larger quantity of heat 50 to the former than to the latter for maintaining uniform heating at relatively low temperature on the constantly rotating retort, stationary closure means for the ends of the retort including conveyor means for moving the charge for a heating through a required time period, and means for exhausting the gases and maintaining a reduced pressure in the retort.
- 60 22. A device for the uniform reduction at a low temperature of an iron ore with coal in intimately mixed pulverized condition, including means for receiving and constantly agitating the charge, said means including a rotary elongated retort, a furnace enclosing the same, means in the furnace outside of the retort for heating the same with a temperature gradient from end to end of the retort, said means including surface combustion means spaced from the retort for obtaining a uniform heating of the same at a low temperature although the said means are at a high temperature for efficient radiation, means for automatically controlling the temperature of the heating means, means for exhausting from the retort the gases therein to produce a decreased pressure, and means for controlling the movement of the charge to and from the retort.
- 75 23. An apparatus for reducing an ore with coal according to a temperature gradient whose maximum temperature is relatively low, including a furnace, an elongated retort therein, firing zones in the furnace spaced along the retort on the outside thereof, said firing zones having means restricting the spread of flame therefrom, said firing zones being spaced more closely near one than near the other end of the retort to produce the temperature gradient, together with means for feeding the charge into the retort at the low temperature end thereof and simultaneously removing the charge from the high temperature end of the retort for a continuous reduction of the iron ore.
- 80 24. A low temperature continuous ore reduction apparatus, including a furnace, a rotary retort therein for receiving and agitating the charge, means co-ordinated with said retort to operate in constant speed relation thereto for feeding a charge to and from the retort, means for heating the retort uniformly peripherally from the outside, said means including a plurality of spaced firing means the spent gases of which flow consecutively in the same direction in the furnace, means in the furnace for drawing off said gases at successive points in the paths thereof, and other means for separately exhausting the gases from the retort.
- 85 25. An apparatus for the direct reduction of iron ore with coal in pulverized condition and without fusion or agglomeration, but with the reduction occurring uniformly and in constant gradation, including a furnace, a rotary metallic retort therein for receiving and agitating the charge, means to uniformly continuously feed materials to and from the retort at opposite ends thereof, said retort being inclined for co-ordinated action with said means for moving and distributing the charge, means for constantly exhausting from the retort the gases therein without withdrawing pulverized particles therefrom, means for exhausting from the inlet end of the retort the gases in the retort to reduce the 90

pressure therein, means for uniformly heating the retort from the outside thereof according to a temperature gradient with the higher temperature being at the outlet end of the retort and the lower temperature at the inlet end thereof, and means for automatically controlling the temperature for any predetermined relation to the pressure.

26. A device including a furnace, a rotary retort therein for receiving and agitating a charge, means in the furnace for heating the retort, said retort comprising a cylinder portion and a relatively stationary end portion, and conveyor means for moving the charge with respect to the retort, said conveyor means being of annular form and engaging the cylinder portion and the end portion to form a closure therebetween.

27. A solid carbon ore reduction device including a furnace, a rotary retort therein for receiving and agitating a charge, high temperature means in the furnace for heating the retort from the outside to a relatively low temperature without flame contact with the retort, said retort being made of a high temperature metal for efficient heat transfer, means at opposite ends of the retort for uniformly continuously feeding into and discharging materials from the retort, means for exhausting the gases in the retort and reducing the pressure therein, and means for automatically regulating the temperature, whereby a desired relation of temperature, pressure and speed of reduction of the ore may be maintained.

28. A device including a rotary metallic retort for large scale metallurgical operations, and heating means therefor, said heating means including firing members extending in spaced relation along the retort, and means enclosing said firing members to cause operation of the latter without flame contact with the retort, the enclosing means being separate of the retort and having a relatively thin radiation wall of large area opposed to and facing the retort wall on the outside thereof to heat the retort by radiation.

29. An apparatus for metallurgical operations, including an elongated retort, means for continuously charging and discharging the same, and heating means for the retort, said heating means including a plurality of firing members extending in spaced relation lengthwise of the retort, and separate combustion means for the several firing members, said combustion means including refractory enclosures of sufficient size and area for causing the firing members to operate without flame contact with the retort and with substantial radiation upon the latter through certain walls of the enclosures.

30. A device including means for receiving and constantly stirring a charge, said means

including a retort, and means for heating the same from the outside, the heating means including a furnace having an internally fired enclosure extending peripherally around the retort in spaced relation thereto, and a burner discharging into the enclosure, the latter having an opening remote from the burner for passing the products of combustion around the retort within the chamber of the furnace.

31. A device including a metallic retort and means for externally heating the same without flame contact with the retort, the heating means including a plurality of spaced tubular channels extending circularly transversely along the wall of the retort in spaced relation thereto, and means to cause combustion in said tubular channels to heat the same to a relatively high temperature for efficient radiation upon the retort from walls of said channels, said channels being of sufficient length to cause the combustion to be terminated therein.

32. A device including a rotary retort, conveyor means coaxial with the retort, said conveyor means extending along and being connected to the wall of the retort, said conveyor means including pockets rotatable with the retort, and means closing the pockets but opening the same in predetermined positions of the rotation for receiving and discharging a material, the last mentioned means coacting with the pockets to form a closure for the retort.

33. A device including a rotary retort, a conveyor therein coaxial with the retort, said conveyor including pockets rotatable with the retort, and relatively stationary closure means for the retort coacting with the pockets to close the same and open an upper and a lower pocket for entrance of material into a lower pocket and discharge of material from an upper pocket.

34. A device including a retort, and closure means therefor, said closure means including a rotary conveyor of ring form including a plurality of pockets arranged so that a pocket receives material in a low position and discharges the material in an upper position, the closure means having other means wholly closing the pocket in intermediate positions.

35. A large scale metallurgical apparatus including a furnace, a retort therein, a plurality of spaced tubular chambers in the furnace independent of the retort and extending along the outside thereof, a porous refractory mass filling said chambers, and firing means for the interior of said chambers whereby a low temperature may be maintained in the retort while operating said refractory mass at high temperature and radiation efficiency.

36. A device including a rotary cylindrical metallic retort, a furnace enclosing the same, a circular refractory tubular enclosure ex-

5 tending around the outside of the retort, a mass of granular refractory material filling said enclosure, and means for discharging a fuel and a supporter of combustion into said enclosure, whereby the fuel is consumed in the interstices of said mass, and the enclosure heats the retort by radiation from the wall of the former.

10 37. A large scale industrial ore reduction device including a rotary retort, a hollow elongated refractory tubular enclosure outside of a relatively small section of the retort in close proximity thereto and spaced from the retort for mechanical clearance, said enclosure being of curved form substantially concentric with the retort, and means for internally firing said enclosure without flame contact with the retort.

15 38. A device including an elongated rotary metallic retort, a furnace enclosing the same, a refractory tube outside of the retort and within the furnace, said tube being disposed around the retort in a plane transverse thereto, said tube being in relatively close proximity to the retort and having only a clearance spacing therewith, a porous mass of refractory in the tube, and means for internally firing the tube.

20 39. A device including a retort, a furnace enclosing the same, a mass consisting of pieces of refractory material, said mass having a continuous wall in the nature of a fused coating disposed toward the retort, and means to fire said mass within the interstices thereof.

25 40. A device including a retort, a furnace enclosing the same, a block in the furnace consisting of pieces of material united by fusion at the surface of the block to provide an otherwise uniformly internally porous block, and means to internally fire said block for heating the retort from the outside thereof by radiation from the block.

30 41. A device, including a furnace, an elongated retort therein, a plurality of tubular refractory rings spaced along the retort and extending around the outside thereof transversely to the retort, a porous refractory mass in said rings, and means to inject a fuel and 35 a supporter of combustion at spaced points in said rings, said rings heating the retort by radiation and having outlet openings for the products of combustion remote from said means.

35 42. A device including a furnace an elongated metallic retort therein, a plurality of refractory tubes extending around the retort transversely thereto around the outside of the retort out of contact therewith, said tubes 40 being spaced from each other lengthwise of the retort, means to inject into the tubes a fuel and a supporter of combustion at spaced points in the tubes, and surface combustion means filling the tubes, the latter having each an opening remote from the injecting means

for discharging the products of combustion into the furnace.

43. A device including a furnace, a rotary retort therein elongated horizontally, a plurality of spaced surface combustion internally fired members extending around the outside of the retort and disposed to heat the same by radiation, said members being mounted in the furnace in spaced relation to the wall of the retort.

44. A device of the character described, including a rotary retort, a stationary transverse closure therefor having a curved wall at an edge thereof and an opening in the wall, an annular series of pockets spaced angularly around the curved wall and revolving with the retort, said pockets being co-ordinated with the curved wall of the closure to cause a movement of the charge in the retort from one to the other side of the said closure through the opening thereof, with the pockets successively registering with said opening.

45. A device including a retort elongated in a generally horizontal direction, a furnace enclosing the retort, and firing means for the retort in the furnace, said firing means including a tubular means extending around the retort in a transverse direction thereto, means for internally firing the tubular means adjacent to a lower portion of the retort, the latter having an opening at an upper portion of the retort for discharging the burnt gases.

46. A device including a rotary cylindrical retort extending in a generally horizontal direction, a furnace enclosing the same, means to constantly feed materials through the retort, and a separate relatively stationary internally fired tubular means extending around a portion of the retort and radiating heat thereon.

47. A device of the character described, including a furnace, a cylindrical retort therein, arcuate refractory tubes in the furnace extending inward of the furnace wall and transversely of the retort, and combustion means to internally fire the tubes, said tubes being spaced from each other to provide radiation on the retort from side walls of the tubes as well as from the walls of said tubes facing the retort.

48. A substantially air tight retort, and enclosed high temperature combustion heating means for heating the retort at a relatively low temperature, the retort being substantially out of contact with the products of combustion, and with the means in which the combustion is taking place, and said heating means being spaced away from and including portions spaced longitudinally along the retort walls to produce and maintain uniform heating conditions, the heat transfer being by conduction and radiation to the retort and the materials therein under treatment.

49. A rotatable substantially air tight re-

5. A retort for reducing metal bearing ores, positive conveyor means associated with the retort to move the materials therein, and combustion heating means for the retort outside of the same, the combustion means being so enclosed that the retort is heated without contact with gases from the combustion means, the retort being out of contact with the means in which the combustion is taking place, said heating means being spaced away from and along the retort walls to produce and maintain uniform heating conditions, the heat transfer being by conduction and radiation to the retort and the materials therein under treatment.
10. 50. A substantially air tight metallic, ore reduction retort and enclosed surface combustion heating means for uniformly heating the retort at a relatively low temperature, the retort being out of contact with the burning gases producing the heat, and with the means in which the combustion is taking place, said heating means being spaced away from and along the metallic retort walls to produce and maintain uniform heating conditions, the heat transfer being by conduction and radiation to the retort and the materials therein under treatment, and means for continuously charging and discharging the materials being treated.
15. 51. A substantially air tight rotary metallic retort and enclosed surface combustion heating means therefor, the retort having stationary end walls and being out of contact with the burning gases producing the heat, and with the means in which the combustion is taking place, said heating means being spaced away from and along the retort side walls to produce and maintain uniform heating conditions, the heat transfer being by conduction and radiation to the retort and the materials therein under treatment, and means for continuously exhausting the gases developed in the retort from the materials being treated as fast as developed and to maintain any desired pressure in the retort, said means communicating with the retort through a stationary end wall.
20. 52. A device of the character described, including a furnace, an ore reduction retort therein, the wall of which includes a metal component, the furnace wall having hollow portions, a mass of porous refractory material associated with said hollow portions through which refractory the combustion gases flow without flame contact with the retort, means to internally fire said hollow portions with the fuel burning in the refractory material with surface combustion and the said material radiating heat on the retort, and automatic temperature control means for regulating the supply of fuel to the firing means.
25. 53. A device including a chamber having a circular upright wall member therein, the

periphery whereof is spaced from the wall of the chamber, and a rotary annular conveyor having a plurality of pockets, said conveyor extending around the outside of the periphery of the member with the pockets in substantial contact with said periphery, certain of said pockets communicating with the space in the chamber on opposite sides of said member.

54. A large scale industrial heating apparatus including a furnace, an elongated chamber therein, and internally fired granular refractory means in the furnace extending around the chamber in a plurality of planes spaced longitudinally of the chamber and transverse to the longitudinal axis thereof, whereby the incandescent heat obtained in said refractory means produces a relatively low temperature in the chamber.

55. An ore reduction apparatus including a furnace, an elongated inclined retort therein, means for continuously feeding a charge into one end of the retort and out from the other end thereof, said means coating with the retort to seal the same against entrance of air, means for heating the retort without combustion therein, the heating means maintaining the retort at a relatively low uniform temperature, and means spaced from and independent of the feeding means for exhausting from the retort the gases therein.

56. An ore reduction apparatus including a retort, means for feeding a charge into and out of the same at opposite ends of the retort, means for heating the retort along an arcuate zone extending around the retort, and means for exhausting from the retort the gases therein, the exhausting means being substantially uniformly spaced from the heating means.

57. An ore reduction apparatus including a retort, means for continuously feeding a charge into and out of the retort, means for heating the retort to produce a volume of gases therein dependent upon the rate of feed and the temperature of the heating means, and means for exhausting the gases from the retort, the heating means being co-ordinated with the feeding and the exhausting means so that the exhausting means normally maintains a reduced pressure in the retort.

58. An ore reduction apparatus including means for receiving and constantly agitating a charge, said means including a retort, means for continuously feeding the charge into and out of the retort, means for uniformly peripherally heating the retort at a relatively low temperature, means for positively exhausting from the retort the gases therein, and means for automatically controlling the heating means to maintain a predetermined temperature-pressure relation in the retort.

59. An ore reduction apparatus including means for receiving and constantly stirring a charge, said means including a retort, means for continuously feeding the charge into and

out of the retort at opposite ends thereof, means for heating the retort according to a temperature gradient, means for forcibly exhausting from the retort the gases therein, the temperature gradient of the heating means increasing from the inlet to the outlet end of the retort, and the exhausting means having such communication with the retort as to cause gases in the retort to flow toward the low temperature end thereof.

60. A device of the character described including a furnace, a rotatable metallic retort therein, said retort being adapted for use in the industrial reduction of ores mixed with coals or similar carbonaceous materials, the retort having a wall all portions of which are spaced at a comparatively large distance from a central point within the retort, radiant heating means disposed at a plurality of points about the outside of the retort to uniformly heat the same, automatic means to control the flow of combustibles to the heating means, co-ordinated with means controlling the flow of materials into, through and out of the retort, and coacting automatic means for forcibly and continuously exhausting all gases as fast as formed, whereby maximum temperatures in retort are maintained below the melting points of solid materials being treated in retort, under conditions therein.

In testimony whereof I affix my signature.
ALFRED MUSSO.
